EXPANSIBLE-FLUID TURBINE.

1,076,952.

Specification of Letters Patent.

Patented Oct. 28, 1913.

Application filed October 29, 1909. Serial No. 525,339.

To all whom it may concern:

Be it known that we, BENJAMIN S. CHURCH, of the borough of Manhattan, city, county, and State of New York, and ABRAHAM B. COX, of the town of Cherry Valley, county of Otsego, and State of New York, have invented certain new and useful Improvements in Expansible-Fluid Turbines, of which the following is a full, complete, and exact description, reference being had to the accompanying drawings, which are hereby made part thereof.

The object of our invention is to devise a turbine more particularly for the use of superheated steam, although well adapted to the use of other expansible fluids which shall be simple in design, and less subject to leakage losses than is the case with existing expansible fluid turbines.

One of the chief losses in efficiency in existing expansible fluid turbines resides in the clearance leakage, to obviate which it is generally necessary in turbines of the "pressure stage" type, most prominently exemplified by the Parson turbine, to make the clearances as small as is mechanically practicable. Even then there is enough clearance leakage loss to increase very considerably what theoretically should be the duty or consumption of the turbine.

The object of our invention is to minimize this clearance leakage, and for such purpose to utilize a very simple mechanical construction, the spirit of which is capable of being embodied in many forms of turbines, although shown only in connection with the turbine invented by B. S. Church, and described in United States Letters Patent, Number 878,118. Such application of our invention will be apparent to any skilled in the art of turbine construction and design.

The clearance leakage loss in a turbine depends upon several conditions: Firstly, upon the mechanical smallness of the clearance which is reduced as much as is mechanically practicable in view of the varying co-efficients of thermal expansion and the rigidity of the materials of which the turbine is composed. Secondly, upon the pressure tending to force the fluid through the clearance, which can be reduced by subdividing the maximum difference in pres-

sure over a large number of successive stages. Thirdly, upon the density or specific volume of the expansible fluid. As respects this last factor it is worthy of note that turbines working with an attenuated fluid, such as "vacuum" or "exhaust steam" turbines, show by far the greatest degree of economy, and, were it not for the vacuum stages, which compensate to a large degree for the losses in the high pressure stages, the steam turbine of to-day would never have become the competitor of the reciprocating engine to the same extent as at present. It is clear therefore that if an expansible fluid of great specific volume can be utilized, the proportion of clearance leakage can be much diminished; but it is not economical from a thermodynamic point of view to use only low pressure or "vacuum" saturated steam, because the thermal energy of such steam is comparatively small; if, however, steam of comparatively low pressure be superheated, its density can be diminished and its thermal energy increased to that of high pressure steam, or even better, and the clearance leakage in a turbine using such steam will be proportionally as small as that of a "vacuum" turbine, while the thermodynamic efficiency can be made to exceed that of the best piston engine using high pressure steam. The reason for this is that the thermodynamic efficiency of the low pressure superheated steam can be made to equal that of high pressure steam, and the turbine using the attenuated superheated low pressure steam will show the well known efficiency of the "vacuum" or "exhaust steam" turbine. It would seem that while high pressure saturated steam is well adapted for use in a piston engine, and very low vacuum steam is not, owing to the limited capacity of the cylinders, and while the exact reverse is ordinarily true of the turbine, a turbine can be constructed possessing the advantages of both, by the utilization of superheated steam of comparatively low pressure.

In Figure 1 is shown a mathematical table illustrating the manner in which a turbine for the use of superheated steam is to be constructed. The table is explained as follows: To begin with it is assumed that sat-

urated steam of 131.49 pounds pressure absolute is generated in the boiler. This pressure was chosen arbitrarily being in the neighborhood of 115 pounds gage, which is 5 a boiler pressure quite commonly used. Saturated steam of 131.49 pounds pressure has a temperature of 348 degrees Fahrenheit. For the purpose of the table it is assumed that 100 degrees of superheat is added. This 10 would make the temperature of the steam 448 degrees, as is shown in column 2 of the table opposite to stage 1. Columns 1 and 18 of the table are arbitrarily chosen for the purposes of the table, and depend upon the 15 amount of subdivision of pressure and temperature necessary to produce the requisite steam jet velocity in view of the speed of rotation for which the turbine is designed. In the Church turbine illustrated, it is de- 20 sired to have a uniform steam jet velocity at every stage, though it will be clearly apparent that in other forms of turbine construction the steam jets might well be of varying velocities, particularly if the steam 25 flow be continuously radial, without departing from the spirit of the table. To estimate the amount of thermal energy necessary to produce a uniform steam jet velocity of 500 feet per second, as shown in column 11 the 30 formula

$$V = (2gM \times E)^{1/2}$$

is used; that is

$$V = (64.4 \times 1 \times 778 \times 5)^{1/2} = 500.055,$$

35 where a unit weight of steam is taken, 778 is the mechanical equivalent of heat and $g=32.2$. It will then be clear that the unit weight—one pound—of steam must part 40 with 5 B. T. U. of thermal energy at every stage in order to develop a uniform steam jet velocity of 500 feet per second, it being assumed that this jet velocity is transmitted to the blades of the turbine and otherwise 45 dissipated except in so far as the small “velocity of approach” is concerned. Column 50 9 gives the specific heat of superheated steam at varying degrees of superheat, which has been determined by several well known experimenters. It will therefore be clear that if 5 be divided by the specific heats given in column 9 the decrease in temperature from stage to stage in column 10 will be obtained. These are then sub- 55 tracted successively to give the temperatures of the superheated steam in column 2. The specific heats in column 9 correspond to the temperatures in column 2 and the mathematical process of obtaining column 2 is 60 cyclical, that is, it consists of first dividing 5 by .564 and obtaining 8.87 then subtracting 8.87 from 448 and obtaining 439.13 (stage 2), then taking the specific heat of 91.93 degrees of superheat column 3; which 65 quantity 91.93 is obtained by subtracting

from 439.13 the temperature of saturated steam at the pressure of 130.18 (stage 2). The pressures in column 4 and the volumes in column 8 are determined by the use of the empirical formula,

$$S_v = .59276 \times \frac{441.4 + T}{P}$$

where T is the temperature given in column 2. This process is continued with the degree of superheat of the steam gradually diminishing, as shown in column 3 until the saturation point is reached as shown on the table by the double line. Column 5 is to be 75 particularly noted. It gives the difference of pressure $P_1 - P_2$ from stage to stage and will be seen to be comparatively small, much smaller than in column 5^a which gives the successive differences of pressure of the saturated steam. In column 8 the volume of 80 steam at 448 degrees temperature and 131.49 pounds absolute pressure is approximately 4 cubic feet per pound weight of steam; a pound of saturated steam at this 85 temperature would require a pressure of almost 400 pounds per square inch and would be in volume not more than 1 cubic foot, while the thermodynamic efficiency in either case would be approximately equal, 90 no argument is required to demonstrate the 95 practical advantages accruing from the use of the low pressure superheated steam; in particular, the great reduction in clearance leakage, to say nothing on the other hand 100 of the practically unworkable boiler pressure of the saturated steam.

If the steam jets be assumed to move at a certain velocity, the size of the ports or nozzles can be easily obtained mathematically by a process of division, consequently 105 column 12 is obtained in this manner from columns 8, 8^a and 11; if there are four ports in each stage, as in the construction illustrated, and the nozzles chosen be two inches wide the successive dimensions given in column 13 are obtained by dividing the 110 quantities given in column 12, by the number 8—there being four ports, each two inches wide. In measuring the nozzles along 115 the circumference of a circle, as in the construction illustrated the angle of inclination must be considered; this circumferential length is given in columns 14 and 15.

In the saturated part of the table columns 120 2^a, 4^a and 6 are obtained from the steam tables. The fall in temperature in column 2^a is such that 5 B. T. U. of thermal energy is transformed into kinetic energy at each stage. This quantity, 5 B. T. U., is obtained 125 by an averaging process, assuming that an equal amount of energy is developed by a uniform drop of 4° in temperature at each stage as shown in column 10^a except as affects stage 14, which divergence will be 130

subsequently explained, which while not absolutely true is sufficiently correct for practical purposes. The formula

$$E = W = q_1 - q_2 + x_1 r_1 - x_2 r_2$$

is used to calculate the amount of thermal energy developed for a given fall of temperature.

Column 7, which is the "condition" of the steam, or its percentage of dryness, is obtained by the empirical formula

$$X_2 = \frac{461 + t_2}{v_2} \left(\log \frac{461 + t_1}{461 + t_2} + \frac{x_1 r_1}{461 + t_1} \right)$$

Column 8^a is obtained by multiplying column 6 by column 7, and the rest of the table is similarly obtained for both the superheated and saturated steam. Column 16 shows an allowance in the lower stages 20 of steam leakage from the upper stages in the construction illustrated. Column 17 makes allowance for guide vanes, which are necessary in the large lower stage ports or nozzles.

Particular emphasis is to be laid on the fact that in the superheated part of the table the quantities given in column 8 are all approximately 4 cubic feet. With diminishing temperature, superheated steam contracts in volume, and does not expand, as is the case with saturated steam; and if the fall in temperature and the diminution in pressure bear the mutual relationship shown in the table, the volume of a unit weight of superheated steam can be kept constant, and all the ports and nozzles are consequently of the same uniform size in the superheated position of the turbine.

There is some uncertainty as to what is the exact specific heat of steam superheated only a few degrees above the saturation point; this is indicated by the irregularity in the fall of temperature in column 10^a at stages 14 and 15; but it will be noted by observing columns 14 and 15 that the transition from ports of a uniform size to those of an increasing cross-section begins very gradually, which would logically point to a very practical solution of what is probably the only uncertain element in the computation. It may be possible that the exact specific heat of superheated steam has not been evaluated closely enough for such a computation as this, but, granted that such is the case, it would seem very practical to provide merely a sufficient number of ports or nozzles of uniform cross-section, and to use more or less of them as results would indicate. The logic of such a method of procedure will be clear upon reasonable consideration of the various columns in the upper part of the table.

We believe that the construction of a turbine for the use of superheated steam having steam ports, nozzles, or passages of uni-

form size and shape, is broadly new, and we desire to claim this feature as completely as possible.

The manner of applying our invention to the Church turbine is illustrated in Figs. 2 and 3 in which S is the shaft which rotates in the bearings B₁, B₂, and carries the wheel disk D which on its periphery is supplied with the bucket blades b, b. Fig. 2 is a view partly in section taken along the line X—X₇₅ of Fig. 3. Fig. 3 is a section taken vertically along the line Z—Z of Fig. 2. In Fig. 2 only a certain number of the blades are shown for the sake of simplicity. The superheated steam enters through the inlet I₈₀ which is Y-shaped and conveys the steam to both sides of the turbine. Each side constitutes practically a separate turbine, this arrangement being chosen to eliminate thrust. It will therefore suffice to describe one side only. The inlet I is omitted in Fig. 2, but it will be clear that the steam traverses the path shown by the solid arrow in Fig. 3 into the chamber C, from which it passes downward and outward through the small ports just below against the blades b, b, and into the chambers 2, 2 (Fig. 2) which correspond with the stage similarly indicated on Fig. 1. From these chambers the steam passes upward as indicated by the dotted arrow in Fig. 3 and between the partitions indicated by the dotted lines in Fig. 2, into the chambers indicated by C₂ (Fig. 2) from which it passes through the corresponding nozzles, against the blades b, b and into the chambers 3, 3 and so on, until it finally reaches the chamber 34 and passes from the exhaust into another turbine, or series of turbines, designed to carry the process down into the proper degree of vacuum. The table shown in Fig. 1 does not show how the principles described are applied to turbines using a vacuum, but the application is so apparent and clear that it would seem amply sufficient merely to refer to it.

The bearings B₁, B₂ are in the form of sleeves or bushings and are supplied with keys k, k to keep them from turning with the shaft. They have spherical exterior bearing surfaces which fit accurately into rings r₁, r₂ and are loosely enough supported so as to turn longitudinally, and thereby to prevent all binding upon the shaft by reason of strain or heat distortion of the casting. The rings r₁, r₂ are held by the hub castings H₁, H₂, which rest upon the A frames A₁, A₂ and inclose the wheel disk D. They also carry the side castings F₁, F₂, which in turn support the cover plate castings J₁, J₂. The center casting L is held between the side castings F₁, F₂ and is provided with a suitable web W, to stiffen it. The port rings P₁, P₂ are supported by the hub castings H₁, H₂ and also by the side

castings F_1 , F_2 , and contain the successive ports or nozzles which are too small to admit of being numbered without confusing the figures, but the construction of which is 5 readily apparent.

The bucket blades b , b are not shown as having any clearance with the parts surrounding them. The clearance is so small as not to well admit of illustration, but are such 10 as is generally used between the motor and the casing of a turbine. The disk is also supplied with a labyrinth Q to prevent leakage of steam into the center of the casing. In practice a certain proportion of steam 15 leaks in from the upper stage chambers and passes out into the lower stage chamber of the turbine casing. To prevent this steam from escaping into the outer air and being wasted thereby, the stuffing boxes V_1 , V_2 , are 20 provided.

While the thrust is practically balanced, there being a clear passage for the steam from one side to the other at every chamber all around the casing there is still some 25 danger of chattering on the part of the motor. To avoid damage to the blades the innermost ring of the labyrinth Q is made to clear the casing by a smaller amount than the ends of the blades, so that the ring shall 30 strike the casing first. As this striking would give rise to unnecessary friction, the shaft is provided with the thrust collar U held between the adjustable thrust rings T_1 , T_2 , which are supported by the frame 35 A_3 , and retained in position by the set nuts or collars N . The frame A_3 is not in any way connected with the rest of the machine, except that it is supported on the same base M , and consequently it is not liable to be 40 distorted by the heat and pressure affecting the other parts.

It will be noted that the turbine mechanism shown is provided with only 34 successive chambers for 34 stages, while the 45 table shown as Fig. 1 calls for 44 stages. As the figures are merely illustrative of the table this is not considered material, because it would, except in very small sizes generally be inadvisable to run through the entire range of temperature and pressure with 50 a single turbine only. Exactly where and how the range of pressure and temperature is to be divided up is a question for the de-

signer, and does not affect the principle involved, which, is that the cross-section of 55 each of the successive nozzles is obtained by the process outlined in the table, and that the nozzles in the superheated portion of the turbine are all of the same, or approximately 60 the same cross-section. It will be quite clearly apparent that the mathematical process described can be equally well applied to a turbine of the Parsons type by spacing and proportioning the rows of 65 blades in the part designed to receive the superheated steam so they shall be exactly alike, and gradually, or at intervals increasing 70 the size of the blades for this expanding saturated steam as in existing machines. The same can be said of all other multiple 75 stage types of turbines and would seem so obvious as not to require illustration.

Having now fully and completely described our invention, what we desire particularly to claim is:

1. A steam turbine having steam passages through which the steam passes at a uniform velocity, part of said passages being of uniform dimensions, and intended to confine the steam while in a superheated condition, and the remaining passages of gradually increasing dimensions for the expanding saturated steam.
2. A turbine for superheated steam having part of its steam passages of uniform size and shape, and part of its steam passages of gradually increasing size and similar shape.
3. A turbine for superheated steam having chambers and nozzles through which the steam passes successively, part of which nozzles are of uniform size and shape, and the remainder of gradually increasing dimensions.
4. A turbine for superheated steam having chambers and nozzles through which the steam passes at a calculated velocity, part of which nozzles are of uniform dimensions for the superheated steam, and the remainder of gradually increasing dimensions for the expanding saturated steam.

BENJAMIN S. CHURCH.
ABRAHAM B. COX.
